FIG. 4.

UNITED STATES PATENT OFFICE.

HARVEY S. PARDEE AND JOHN A. DEWIRE, OF CHICAGO, ILLINOIS, ASSIGNEES, BY MESNE ASSIGNMENTS, TO THE KINGSLEY-MILLER COMPANY, OF CHICAGO, ILLINOIS, A CORPORATION OF ILLINOIS.

RADIATOR CAP.

Application filed May 27, 1921. Serial No. 473,113.

Our invention relates to improvements in radiator caps and more particularly to those designed as a mounting for motometers and having means for locking the same 5 in place to prevent theft.

One object of the invention is to provide means for automatically locking a radiator cap and motometer in position by simply screwing the structure into place, thereby dispensing with a key, such as is usually required where the motometer is locked against theft. Another object is to provide an improved motometer lock which cannot be unlocked or removed from the 10 radiator except by removing the radiator from the car, as, for example, when repairing the radiator. A further object is to provide not only a rugged structure but one which is ornamental as well, having a cover 15 plate in front on which the monogram of the owner, the name of the car or some ornamental design may be placed in conspicuous position.

In the accompanying drawings, in which 20 two embodiments of the invention have been illustrated,

Fig. 1 is a front elevation of one form of the device;

Fig. 2 is a section in two different planes 30 on the line 2-2 of Fig. 1;

Fig. 3 is a side elevation of the device partly in section; and

Fig. 4 is an elevation partly in section of another form of the invention.

The structure shown in Figs. 1, 2 and 35 comprises a main supporting ring or adapter 10, having an enlarged lower flange 11, which is internally screw-threaded to engage the screw-threaded upper end of the radiator neck 12. The adapter 10 is surrounded by the body of the cap in the form of a second ring 13, locked to the adapter by a piston ring 14, received within suitable grooves in the two members. After 40 one part has been telescoped over the other until the grooves match, the piston ring, which is under compression, snaps into place, i. e., it expands and overlaps the joint thereby locking the parts together, 45 although permitting the cap to rotate about the adapter. Said cap may be of any suitable design and is shown as provided with ornamental extensions or arms 15, which

may also serve as convenient handles for rotating it. 55

In order to lock the outer and inner rings against relative rotation in one direction while permitting free relative rotation in the opposite direction, we provide preferably a pair of ball clutches arranged on opposite sides of the inner ring. Each comprises a steel ball 16 carried loosely within an inclined slot 17, as shown in Figs. 2 and 3. When the handles 15 are grasped and the outer ring rotated in a direction to screw the inner ring down over the screw-threaded neck 12, the balls 16, which are normally retained by gravity near the lower ends of said slots, are moved toward the lower end of their respective slots thereby gripping the inner ring 10 and permitting its screw-threaded extension 11 to be screwed down hard on said neck. Rotating the outer ring 13 in a direction to unscrew the device from the radiator results simply 75 in free rotation of the outer ring 13 upon the inner ring 10, as the balls 16 are rolled up their inclined grooves by friction far enough to release their grip on the adjacent surfaces but not far enough to bind at the upper ends of said grooves. The vertical height or width of the flange 11 below the lower end of the cap is insufficient to permit of the application of an ordinary tool 80 such as a Stillson wrench so that after the device has once been screwed into place it is impossible to remove it, as long as the radiator remains on the car and right side up.

In order to insure further against theft, however, we may provide a loose collar 18, surrounding said flange 11 and resting on the shoulder at the upper end thereof. If this collar were gripped by a pipe wrench, said collar would simply rotate about flange 11, thereby preventing unauthorized removal of the device. 90

It will be noted that if the entire radiator is removed in repairing the same in a garage, for example, said radiator may then be turned upside down, resulting in the reversal 100 of the locking action of the ball clutches. That is, in an inverted position the balls tend to roll to the opposite ends of the grooves 17, as a result of which the outer ring may rotate the inner ring in a direction to permit unscrewing of the device from 105

the radiator, but the cap will turn freely when rotated in the opposite direction.

The cap includes a hinged cover 19, the hinge being arranged preferably at the front. Said hinge consists of a pin 20, passing through two lugs on the cap and a single lug on the cover. The hole for the pin does not pass completely through one of said cap lugs, making it difficult or impossible to drive the pin out. Said pin has a driving fit in said cap lugs, rendering it difficult or impossible to withdraw said pin, as the exposed end does not project beyond its supporting lug.

15 A knurled locking screw 21 passes loosely through an opening in the rear of said cover and engages within a screw-threaded recess 22, to lock the cover in place. Said cover is provided with a beveled undersurface 23, arranged to bear against a yielding gasket 24, made preferably of rubber to insure that the cap when closed will be water-tight and steam-tight. Said rubber gasket rests on a thin metallic gasket 25, comprising preferably a flat ring of brass or copper. During relative rotation of the outer and inner rings the rubber gasket has a tendency to adhere to said outer ring and would also tend to adhere to the top of the inner ring on which it rests were it not for the copper gasket, which slides freely on said inner ring, thereby preventing the rubber gasket from binding and restricting the turning movement.

The motometer 26 may be of any suitable type either the thermometer type or the electric signal type and is held to the cap between a shoulder 27 and a nut 28, on its screw threaded stem 29. Said stem also carries a second nut 30 bearing against a washer 31, of some soft metal such as annealed brass or copper and having a raised central portion. Said washer is of such diameter as to be received loosely within the undercut groove 32. In assembling the parts, the nut 30 is tightened until the crowned washer 31 flattens out somewhat and increases its diameter sufficiently to lock it permanently within the groove 32. This washer prevents access to the nut 28, which holds the motometer to the cap, and thus prevents removal of the motometer from the cap. Accidental or intentional loosening or removal of the nut 30 does not result in loosening the washer 31, which cannot be removed except by destroying or otherwise mutilating the washer or some other part of the structure.

The front part of the ring 13 is enlarged to form a support for a plate 33. Said plate may carry any suitable insignia and may be ornamental. It is shown in the form of a shield bearing the initial of the owner. It is readily turned to face the front by simply rotating the outer ring by means of the arms 15, the friction between the parts preventing further accidental movement.

In filling the radiator with water the operator simply unscrews the fastening screw 21 and swings the cap up. If the motometer is in the way, in this position, the entire cap may be turned until the shield faces the rear. After filling the radiator the cap is turned farther in the same direction to bring it to normal position.

Fig. 4 shows a modification wherein the outer ring 34, conceals the lower end of the inner ring and prevents the application of a wrench thereto. Said lower end may be internally screw-threaded as in Fig. 3 or in either form of the device the lower extension may be exteriorly screw-threaded 80 to apply to radiator inlets which are screw-threaded on the inside instead of the outside. Such a screw-threaded extension is shown at 35 Fig. 4.

It will be seen that we have provided a 85 construction which is very rugged, which can be readily applied to the radiator without special tools and which after being applied, is to all intents and purposes permanently connected with the radiator so that it cannot be removed without badly mutilating it, except by turning the radiator upside down. The locking device is automatic and dispenses with the necessity of equipping the cap with some standard lock necessitating the carrying of an additional key which latter is always objectionable.

Various modifications of the structure illustrated herein, may be made by those skilled in the art, within the scope of the 100 appended claims.

We claim as our invention:

1. In combination, a motometer, a cap supporting the same and having supporting lugs, means for locking said cap to a radiator neck, said means comprising a pin having a driving fit within and passing partly through the supporting lugs, means for locking said motometer to said cap comprising an annular groove in said cap, a screw threaded extension on said motometer, a nut on said screw-threaded extension, and a washer with an offset central portion engaged by said nut whereby said washer may be spread to enter said groove and permanently lock said motometer in place.

2. A device of the type described comprising an annular hollow member adapted to be connected to a radiator; a movable cover for said member, retaining means securing the cover against theft, said cover having an opening therein adapted to receive the shank of a motometer with locking means therefor on the inside of the cover, an annular engaging portion on the interior of the cover, and a member disposed on said engaging portion whereby access to the motometer locking means is prevented, said annular engaging portion having the form of an undercut V-shaped groove with one wall facing 130

downwardly forming a shoulder and the other wall of the groove extending downwardly and inwardly making an acute angle with said shoulder.

5 3. The combination of an internal collar having an opening therethrough and having means for attachment to the filling opening of a radiator, an external collar fitting around said internal collar, a closure for said 70 external collar, means permanently securing said closure to the external collar, said means permitting the closure to be moved to permit access to the interior of said collar and means locking together said collars against theft.

10 4. The combination of an internal collar having an opening therethrough and having means for attachment to the threaded filling opening of a radiator, an external collar fitting around said internal collar, a closure 75 for said external collar having an opening adapted to receive a motometer, a pivot pin permanently securing said closure to the external collar, and means locking together said collars against theft.

15 5. The combination of an internal collar having an opening therethrough and having means for attachment to the threaded filling opening of a radiator, an external collar movably fitting around said internal collar 80 30 when the device is assembled for use, a closure for said external collar having an opening adapted to receive a motometer, a pivot pin permanently securing said closure to the external collar, and means locking together 85 said collars against theft.

35 6. The combination of an internal collar having an opening therethrough and having means for attachment to the threaded filling opening of a radiator, an external collar fitting around said internal collar, a closure 90 for said external collar having an opening adapted to receive a motometer, a pivot pin permanently securing said closure to the external collar, and means locking together 95 40 said collars against theft.

45 7. The combination of an internal collar having an opening therethrough and having means for attachment to the threaded filling opening of a radiator, an external collar movably fitting around said internal collar when the device is assembled for use, a closure 100 for said external collar having an opening adapted to receive a motometer, a pivot pin permanently securing said closure to the external collar, and means locking together 105 said collars against theft.

50 8. The combination of an internal collar having an opening therethrough and having means for attachment to the threaded filling opening of a radiator, an external collar movably fitting around said internal collar when the device is assembled for use, a closure 110 for said external collar having an opening adapted to receive a motometer, a pivot pin permanently securing said closure to the external collar, and means locking together 115 said collars against theft.

55 9. The combination of an internal collar having an opening therethrough and having means for attachment to the threaded filling opening of a radiator, an external collar fitting around said internal collar, a closure 120 for said external collar having an opening adapted to receive a motometer, a pivot pin permanently securing said closure to the external collar, and means locking together 125 said collars against theft.

60 10. The combination of an internal collar having an opening therethrough and having means for attachment to the threaded filling opening of a radiator, an external collar fitting around said internal collar, a closure 130 for said external collar having an opening adapted to receive a motometer, a pivot pin permanently securing said closure to the external collar, and means locking together said collars against theft.

permanently securing said closure to the external collar, means locking together said collars against theft and means permitting relative rotation between the collars in one direction but preventing relative rotation in the other direction.

11 9. The combination of an internal collar having an opening therethrough and having means for attachment to the threaded filling opening of a radiator, an external collar surrounding said internal collar, a closure for said external collar adapted to carry an auxiliary device, means permanently securing said closure to the external collar, said means permitting the closure to be moved to permit access to the interior of said collar and means maintaining said collars in assembled relation against theft.

15 10. The combination of an internal collar having an opening therethrough and having means for attachment to the threaded filling opening of a radiator, an external collar surrounding said internal collar, a closure for said external collar adapted to carry an auxiliary device, a pivot pin permanently securing said closure to the external collar, and means maintaining said collars in assembled relation against theft.

20 11. The combination of an internal collar having an opening therethrough and having means for attachment to the threaded filling opening of a radiator, an external collar movably surrounding said internal collar when the device is assembled for use, a closure for said external collar adapted to carry an auxiliary device, a pivot pin permanently securing said closure to the external collar, and means maintaining said collars in assembled relation against theft.

25 12. The combination of an internal collar having an opening therethrough and having means for attachment to the threaded filling opening of a radiator, an external collar surrounding said internal collar, a closure for said external collar adapted to carry an auxiliary device, a pivot pin permanently securing said closure to the external collar, and means maintaining said collars in assembled relation against theft.

30 13. The combination of an internal collar having an opening therethrough and having means for attachment to the threaded filling opening of a radiator, an external collar movably surrounding said internal collar when the device is assembled for use, a closure for said external collar adapted to carry an auxiliary device, a pivot pin permanently securing said closure to the external collar, and means maintaining said collars in assembled relation against theft.

35 14. The combination of an internal collar having an opening therethrough and having means for attachment to the threaded filling opening of a radiator, an external collar surrounding said internal collar when the device is assembled for use, a closure for said external collar adapted to carry an auxiliary device, a pivot pin permanently securing said closure to the external collar, and means maintaining said collars in assembled relation against theft.

- opening of a radiator, an external collar surrounding said internal collar, a closure for said external collar adapted to carry an auxiliary device, a pivot pin permanently 5 securing said closure to the external collar, means maintaining said collars against theft and means permitting relative rotation between the collars in one direction but preventing relative rotation in the other direction.
15. In combination, a closure for a radiator filling opening, means including two collars one fitting around the other for connecting said closure to said radiator but permitting a limited opening movement thereof, said means being releasable from said radiator only when said radiator is in abnormal position.
16. In combination, a closure for a radiator filling opening, means including two collars relatively movable in assembled condition, one fitting around the other, for connecting said closure to said radiator but permitting a limited opening movement thereof, said means being releasable from said radiator only when said radiator is in abnormal position.
17. In combination, a closure for a radiator filling opening, means for connecting said closure to said radiator but permitting a limited opening movement thereof, said means being releasable from said radiator

only when said radiator is in abnormal position, a one way clutch reversible upon inverting the radiator being associated with 35 said means.

18. A combined radiator cap and indicator comprising an indicator, a cap member, means for securing the indicator to said cap member against unwarranted removal 40 to prevent theft, and means securing the cap member and indicator to the projected neck portion of a radiator to prevent unwarranted removal and theft thereof when attached to the radiator, said last mentioned 45 means being attached to the cap and indicator to permit opening thereof for filling the radiator.

19. A combined radiator cap and indicator comprising an indicator, a cap member, means for securing the indicator to said cap member against unwarranted removal to prevent theft, and means securing the cap member and indicator to the projected neck portion of a radiator to prevent unwarranted removal and theft thereof when attached to the radiator, said last mentioned 55 means being hingedly connected to the cap and indicator to permit opening thereof for filling the radiator.

In testimony whereof, we have subscribed our names.

HARVEY S. PARDEE.
JOHN A. DEWIRE.
